KEY HOLDER

Robert C. Pfau, Minneapolis, Minn.

Application May 29, 1945, Serial No. 596,464

4 Claims. (Cl. 70—456)

1

This invention relates to key holders and has for one of its objects to improve generally upon such articles and more particularly to provide the same for readily attaching keys to and removing the same from the holder and at the same time facilitate the handling of the desired key in the dark or inadequate light for discernability and also to provide for the folding of the cover or casing of the article compactly so as to enable the same to be carried in one's pocket without discomfort or causing undue wear upon the pocket.

Other objects and advantages to be attained will hereinafter more fully appear in the following description.

A practical but non-limiting exemplification of the invention is illustrated in the accompanying drawings, in which—

Figure 1 is a plan view of a key holder constructed in accordance with the invention with the flap portions of the covering or case opened out flatwise;

Figure 2 is a fragmentary plan view, on an enlarged scale, illustrating the holding means for the releasable end portion of the key holding element;

Figure 3 is an end view of the parts shown in Figure 2;

Figures 4 and 5 are respectively side elevation and top plan views of a practical form of spacer element;

Figure 6 is a detail view of a practical form of a marker or identification element;

Figures 7, 8 and 9 are fragmentary views illustrating a modification of the releasable retaining means for the key carrying element of the device of the invention; and

Figure 10 is a detail view illustrative of a practical way of detachably applying a knob element of the device to its supporting member.

Referring now to the drawings in detail, the numeral 10 designates, generally, a case or outer covering for the key holder. As shown, this case or covering 10 comprises a generally rectangular major body portion 11, two side flap portions 12, 13, respectively, and an end flap 14. However, while this showing is of a practical form it is, of course, understood that, as far as the present invention is concerned, this part of the device may be made in any other desirable or approved form.

Secured to the inner face of the body portion 11 of the case or covering, near the flap end 14 thereof, is a reinforcing and supporting bar 15 of metal or any other suitable rigid material.

2

At one end of the bar 15 is formed integrally or otherwise provided a right angular extension 16 in which an eye member 17 is mounted swivelly, as at 18. A key carrying and supporting element 19, of either a rigid or flexible character, and either in the form of a chain or a bar, as may be desired, is hingedly or swingably attached to said eye 17 to permit universal movement of said element 19. At the opposite end of the element 19 is either hingedly or rigidly attached, as may be desired, a relatively shorter extension or bar 20 having at its outer end a knob or handle member 21.

The extension or bar member 20 is releasably attached and supported in a frame 22 which is either formed integrally with or rigidly attached to the adjacent end portion of said reinforcing and supporting bar 15. As shown more clearly in Figures 2 and 3, the frame 22 is of a generally rectangular, substantially U-shaped form comprising a base portion 23 and two opposite upstanding side members 24, 25. The frame thus formed is open at its top, as indicated by the arrow and the designating numeral 26 (see Figure 3). It is through this opening 26 that the extension or bar member 20 is movable into and out of the frame 22 in securing said member 20 to and removing the same from its support in said frame 22.

30 The support for the member 20 of the element 19 comprises, as shown more clearly in Figure 3, a spiral spring element 27 which is secured at one end portion to the side member 25 of said frame 22, as at 28. This spring element 27 is 35 coiled inwardly from its attached end portion 28 and terminates at its inner end portion with a small loop portion 29 at the extreme end of which is formed integrally or otherwise provided a knob or head 30. It is within this inner loop portion 29 of the spring element 27 that the extension or bar member 20 of the element 19 is supported and normally releasably retained in position.

It is a simple matter to place the member 20 of the element 19 within the looped inner portion 29 of the spring element 27, by grasping said member 20 and forcibly moving the same sideways between the wall 24 of the frame 22 and the adjacent peripheral spring portion 31 which is in tangential contact with or closely adjacent to said wall 24. Then, by carrying said member 20 downwardly and under the lower peripheral portion 32 of the outer convolution of the spring element 27 and the base 23 of said frame 22, thence upwardly and around between the several convolutions of the spring element until said mem-

ber 20 rides into the inner looped portion 29 of said spring element, where said member 20 is retained by the head 30 on the inner end of the spring element 27, which head 30, owing to its relative angular position within the adjacent convolution of the spring element is sprung inwardly as said element 20 is forced by said head 30, and after the element 20 has passed said head 30 the latter, by the reaction of the adjacent portion of the spring element 27, springs back in engagement with the head 21 of said member 20 or else in contact with the adjacent portion of said member 20. By the same token, and a reversal of movement of the member 20, the latter is, by a revolving movement of said member 20, moved out of said spring element 27 and is free to be moved out through the opening 26 of the frame 22 to be there held by hand in manipulation of the element 19 in placing keys upon or removing the same from said element 19.

In some uses of the device of the present invention the element 19 may be made to carry only the keys, two of which latter are indicated, as at 33 and 34, for exemplification, in Figure 1. It is, of course, understood that said element 19 may be made to carry any desirable number of keys thereon, and, in some cases, for enhancing the advantages of the holder and particularly in readily identifying the desired key to be used, especially in the dark or inadequate light, suitable spacer elements 35, a practical example of which is illustrated in Figures 4 and 5, may be provided on said element 19 between the respective keys strung thereon. These spacer elements 35 may be of any suitable form and character as to material used, and the same may be either rigid or flexible, but, for practical purposes, it is preferable to make the elements 35 of plain cylindrical cross section with an axial bore therethrough. So, too, said elements 35 may be plain cylindrical with squared ends or, as shown more clearly in plan view in Figure 5, the opposite end portions of said elements 35 may be beveled off, as at 36.

In addition to the aforesaid spacing elements 35, special marker or identification elements 37 may be placed between the several keys on the element 19, one correlated to and adjacent each key to facilitate the selection of the particular key desired to be used. As shown, these marker or identification elements 37 may be in the form of centrally apertured circular discs (see Figure 6), and marked with identification indicia.

From the foregoing it is evident that a key holder is produced on which the several keys 55 may be placed and removed, at will, conveniently selected and handled in use, and the folded and closed case or covering containing the keys can be placed and carried conveniently in the pocket and without causing any undue wear on the 60 pocket.

The illustrated exemplification of the invention is but one practical form and adaptation of the invention and the same may be modified and changed in many respects without departing from the spirit of the invention as defined in the appended claims. The invention, therefore, is not limited to the specific construction and arrangement shown.

An illustrative modification of the invention 70 is shown in Figures 7, 8 and 9 of the drawings. This modification concerns the releasable holding means for the end extension and manipulating member 20 of the key carrying and supporting element 19. The parts 10, 15, 20, 21, 22,

23, 24 and 25 are the same as in the first herein described structure. However, a different form of spring retainer element 38 is provided in place of the aforesaid spring element 27.

5 The spring element 38 is made in a single, open-ended loop and in an oval form with the smaller end of the oval open, as at 39, in the normal shape of the spring (see Figure 7). One end portion of the spring element 38 is screwed, riveted or otherwise fastened securely to the leg 25 of the supporting bracket 22, as at 40. The free end of said element 38 is provided with a laterally extended knob 41.

In the normal position and condition of the spring element 38, the periphery of its portion, near its free, knobbed end 41, is urged into yieldable, tangential contact, as at 42, against a curved supporting member 43 (see Figure 7). The member 43 is a metal strip of ample rigidity when secured in place on the bracket element 23 yet possessing certain inherent resiliency so that, when one end thereof is seated in the corner portion of the bracket element 22 at the inner end of the leg 25, as at 44, it can be bent curvedly between its ends, substantially as shown, with its opposite end portion screwed, riveted or otherwise suitably secured to the outer end portion of the opposite leg 24 of the bracket element 22, as at 45.

15 In applying the end extension 20 of the key carrying and supporting element 19 for releasable holding thereof by the spring element 38, in the modified form of holder, the part 20 is first placed in the opening 26, as in the first herein described modification, and then moved forcibly inward between the curved support 43 and adjacent portion of the spring element 38, as indicated by the dotted line and full line showings in Figure 9, which spreads the element 38 away from the support 43 substantially as shown. Continued movement of the member 20 and its carried knob 21, inwardly, until said parts are arrested in crotch at the corner juncture of the base 23 and leg 25 of the bracket element 22, permits the spring member 38 to react, by its inherent resiliency, and return to its normal set position, as shown in Figure 7. With the parts thus positioned, the key carrier extension 20 is held securely in place by the spring element 38 bearing thereagainst laterally thereof, and at the same time the cooperating adjacent knob portions 21 and 41, provided respectively on the key carrier element 20 and the spring element 38, prevent inward longitudinal movement of the member 20 or its disengagement from the holding bracket 22 that might occur if it were not so retained.

20 To disengage the held element 20 the operation is in reverse order to that in which the attachment is accomplished as just above described. That is to say, by merely grasping the knob 21 and moving the element 20 out of place from under the spring element 38, or, if found necessary or of facility, by also grasping the knob 41 and forcing the spring element away from the curved support 43 to more readily pass the element 20 therebetween.

25 It is here noted that the knob elements 21 and 41 may be applied to their respective companion and carrying parts in any desirable manner, being either formed integrally thereon or made detachable therefrom, in which latter case, the knobs may be applied substantially as indicated in Figure 10, or otherwise, as may be more practical or preferred. As shown in Figure 10 the application of the knob to its companion carry-

ing element is accomplished in a simple conventional form, that is to say, by merely screw-threading the end portion of the companion carrying element, as at 20', and providing the knob element 21 (or the element 41, as the case may be) with a counterpart, internally screw threaded, diametrical bore to fit on said screw threaded supporting portion.

As hereinbefore stated, the first structure described herein, is susceptible of considerable modification within the purview of the invention as defined in the appended claims. The same is true of the modification just hereinbefore described.

Having thus described the invention, what is claimed is:

1. A key holder comprising a supporting base, a key-receiving and supporting element having a universally swingable attachment at one end to said supporting base, and means upon said supporting base remote from said universally swingable end attachment of said key-receiving and supporting element and arranged and adapted to detachably receive and support the opposite end of said key-receiving and supporting element, said means comprising a spirally formed spring element supported at one end on said supporting base and the key-receiving and supporting element having at its end opposite to that which is universally swingably mounted an extension member arranged and adapted to be moved around and within the convolution of the spring element until it is received and releasably supported by the innermost convolute portion of the spring element.

2. A key holder comprising a supporting base, a key-receiving and supporting element having a universally swingable attachment at one end to said supporting base, and means on said supporting base remote from the universally swingable end attachment of said key-receiving and supporting element and arranged and adapted to detachably receive and support the opposite end of said key-receiving and supporting element, said means comprising a spiral spring element fastened supportedly at one end on an adjacent portion of said supporting base and looped convolutely from its supported end with its opposite end forming a terminal of its innermost convolution and said inner end of the spring having an enlargement thereon, and the end of said key-receiving and supporting element op-

posite to its universally swingable supported end having an extension provided at its outer end with an enlargement, said extension being movable around and within the convolution of said spring element until it reaches a restricted opening defined by its innermost convolution, thereby to be supported and retained, and whereby the release of said key-receiving and supporting element from said spring element is accomplished by a correlated manipulation of the enlarged ends of said spring element and said key-receiving and supporting element extension and with a reversely revoluble movement of said extension around and within the convolution of said spring element until said extension is freed from engagement with said spring element.

3. A key holder comprising a supporting base, a key-receiving and supporting element having a universally swingable attachment to said supporting base, and means upon said supporting base remote from said universally swingable end attachment of said key-receiving and supporting element and arranged and adapted to detachably receive and support the opposite end of said key-receiving and supporting element, said means including an extension member carried by the end of the key-receiving and supporting element opposite to that of the universally swingable end thereof, and a convolute spring means supported on said base and in association with said extension member for releasably supporting the latter.

4. A key holder as set forth in claim 3, wherein the means for detachably receiving and supporting the free end of the key-receiving and supporting element comprises an inclined abutment member on the supporting base in transversely opposed relation to a perpendicular abutment member on the base and the spring means is fastened at its supported end portion on said perpendicular member and its free end portion is disposed in cooperatively opposed relation to said inclined abutment member.
